US00D710111S

(12) **United States Design Patent**
Ding et al.

(10) **Patent No.:** US D710,111 S
(45) **Date of Patent:** ** Aug. 5, 2014

(54) **TOOTHBRUSH**

(71) Applicant: **Colgate-Palmolive Company**, New York, NY (US)

(72) Inventors: **Xiang Ji Ding**, angZhou (CN); **Yu Liu**, Wuxi (CN); **Wen Jin Xi**, Shanghai (CN); **Al Sprosta**, Maplewood, NJ (US); **Kenneth Waguespack**, North Brunswick, NJ (US)

(73) Assignee: **Colgate-Palmolive Company**, New York, NY (US)

(**) Term: **14 Years**

(21) Appl. No.: **29/464,192**

(22) Filed: **Aug. 14, 2013**
